LUBRICATING APPARATUS

Albert W. Arnold, Miami, Fla.

Application November 3, 1932, Serial No. 641,065

7 Claims. (Cl. 103—153)

This invention relates to an improvement in lubrication apparatus, such as is employed for instance for lubricating machinery or automobiles, or the like, wherein a lubricant, such as 5 grease, is forced under pressure to the parts of the machine, in order to insure complete lubricating thereof.

My invention utilizes fluid actuated pumping means for the lubricant which pumps the lubricant from a container to the bearings of the machine elements and has automatic means for controlling the supply of fluid to the pumping means. It is intended to use compressed air primarily as the fluid actuating means and I have a valve 10 mechanism for controlling the supply of air to the pump piston, and which valve means is controlled automatically in accordance with the movement of the pump piston, so as to be opened when the piston returns to its backward position, but is closed with a snap action when the piston moves to its extreme outward position.

The pump piston has a cup washer at the end thereof, and in order to prevent undue wear of said cup washer, while at the same time to draw in a full volume of lubricant from the container, I provide slots in the sides of the pump cylinder through which the pump piston moves. These slots, rather than mere holes, prevent a 15 wearing out of the cup washer as would be caused by a series of holes in the sides.

In the accompanying drawings,

Fig. 1 is a perspective view of my complete invention;

Fig. 2 is a partial sectional view on the line 2—2 of Fig. 5;

Fig. 3 is a side elevation of the invention;

Fig. 4 is an end elevation thereof;

Fig. 5 is a vertical sectional view on the line 5—5 of Fig. 3;

Fig. 6 is a sectional view through the pump cylinder structure and the lower end of the tank;

Fig. 7 is a detail transverse sectional view on the line 7—7 of Fig. 6;

Fig. 8 is a partial sectional view on the line 8—8 of Fig. 5; and

Fig. 9 is a similar view on the line 9—9 of Fig. 5.

I have shown the invention as mounted on a wheeled truck in order to permit it to be moved easily about from place to place, the truck body or platform being designated 1, and mounted on main wheels 2 at one end thereof, and a swiveled guide wheel 3 at the other end thereof, which permits the truck to be easily turned when moving from place to place.

Mounted on the truck body or platform 1 is a casting or block 4, shown in section in Fig. 6, and which block supports the lubricant tank 5, thereon, the tank being shown as having its bottom bolted to the top face of the block 4 and resting thereon, as shown in Fig. 6. The bottom of the tank 5 has a discharge opening which is in open communication with a chamber 6 in the block 4. Extending transversely through the block 4, and through the chamber 6, is a bushing 7, which forms the pump cylinder and within which the pump piston 8 operates. The outer end of the pump piston 8 has a cup washer 9, detachably secured thereto, and forming a packing for the piston.

The sides of the bushing 7 having elongated slots 10 formed therein and which allow the lubricant to flow or be drawn into the cylinder 7. By having the slots 10 elongated rather than small holes along the bushing 7, the cup washer 9 will last much longer than if it was used with the holes.

The free end of the pump cylinder 7 is closed by a spring pressed check-valve 11, and the extreme end thereof may be connected with a hose 12, shown in Figs. 1 and 3, leading to the bearings or machine parts to which the lubricant is to be supplied.

Also mounted on the truck body 1 at the opposite end portion thereof from the block 4, is a valve casing 13, within which is mounted a tapered control valve 14, shown in section in Figs. 5 and 9. The valve 14 has a fluid supply opening 15, extending therethrough in alignment with a fluid passageway 16 in the casing 13, which passageway is connected at one end with a cut-off valve structure designated generally by the numeral 17, and which cut-off valve structure may be of any well-known form suitable for manually regulating the supply of fluid to the passageway 16. A hose 18 or other conduit may be used for supplying fluid to the valve. Preferably I employ compressed air since it is usually more convenient and available, but any other suitable fluid desired may be used.

The opposite ends of the fluid supply opening 15, and passageway 16, are flared or bell-mouthed, as indicated at 15a and 16a, respectively. The purpose of this is to prolong the period that the fluid passes through the fluid supply opening and the fluid passageway, and insure a pressure predetermined by the size of the opening 15, through the valve and the passageway 16. In this way I am enabled to use a relatively small fluid supply opening 15, through the valve 14, and fluid

passageway 16, and still get the effect of a larger opening and passageway.

Attached to one side of the valve casing 13 is a power cylinder 19, within which is mounted a power piston 20 having the pump piston 8 attached thereto and moved by movement of the power piston 20. A spring 21 is shown in Fig. 9, as being interposed between one side of the power piston 20 and the other end of the cylinder 19 to return the piston to its retracted position and at the same time to draw the pump piston 8 back in its cylinder 7 to take in a new supply of lubricant.

Attached to the inner end of the piston 20, is a cup washer 22 with its apex arranged approximately in alignment with the passageway 16 and secured to the end of the piston 20 as by a screw 23. This cup washer is preferably of leather and lies flat against the conical end of the piston but has flaring sides 24 which lie against the sides of the cylinder 19, so that the fluid being diverted by the conical shaped cup washer 22 will act on the sides 24 thereof, which forms sealing portions around the piston as an effective packing therefor.

The orifice 15 through the valve 14 when registered with the passageway 16, admits fluid under pressure to the end of the power cylinder 19 and causes outward movement of the pistons 20 and 8. When these have moved to their outer positions, a discharge orifice 25 is brought into registry with an end of the passageway 16 to release the fluid from the cylinder 19 into the atmosphere and upon this reduction in pressure the spring 21 returns the pistons to their retracted positions.

The means for turning the valve 14 in synchronism with the movement of the pistons is shown in Figs. 1, 2, 3, 5 and 8. Referring to Fig. 5, the valve 14 which is conical and which is fitted in a similarly shaped seat, is held against its seat by means of a spring 26, which is arranged in a recess 27 in the valve, so that one end bears against the valve, while the other end bears against a plate 28 rigidly fixed to the casing 13 where it is held in place by bolts and/or screws 29. The expansive action of the spring 26 keeps the valve 14 properly seated, even though turned in the casing.

The plate 28 has an arcuate slot 30 therein through which projects a pin 31 attached to the end of the valve 14, so as to be rigid therewith. A bolt or journal pin 32 is supported by the plate 28 on which bolt or pin 32 is journaled a cam disc 33, shown in Fig. 2, which disc has a cam projection 34 on one side thereof, and has arcuate slots 35 and 36 on diametrically opposite sides of the journal 32, the slot 35 receiving the pin 31 attached to the valve 14. An actuating disc 37 is journaled on the pin or bolt 32 in face abutting relation with the cam disc 33 and the actuating disc 37 carries a pin 38 in position to project into the slot 36 of the cam disc 33. The actuating disc 37 has an arm 39 pivotally connected with one end of a connecting rod 40, the opposite end of which is pivotally connected with a head member 41 rigidly attached to the pump piston 8, so as to be moved therewith and by such movement to turn the actuating disc 37 on the journal 32. The rocking of the valve 14, causes the fluid supply opening 15, to move out of alignment with the passageway 16, but the bell-mouth ends, 15a and 16a, being of greater diameter than the diameter of the opening 15, and passageway 16, make possible the further rocking of the valve

14, after the latter has moved the fluid supply opening 15, out of direct alignment with the passageway 16. The result of this is to start the movement of the valve 14, thus enabling the cam disc 33, to continue to complete the rocking movement of the valve.

The periphery of the cam disc 33 and the cam projection 34 thereof have a roller 42 bearing thereon, being carried by a rod 43 which is pressed against the periphery of the disc by a spring 44 as shown in Figs. 1, 2 and 3. The rod 43 is slidably mounted in guides 45 carried at a side of the cylinder 19.

There will normally be a constant pressure of fluid in the inlet side of the passageway 16 and when the valve 14 is turned to the position shown in Fig. 9, this pressure will act on the piston 20 forcing the same outwardly against the tension of the spring 21 and also forcing the pump piston 8 to the left in Fig. 6 which forces the lubricant out of the cylinder 7 to the desired point of lubrication. As the piston 8 moves outwardly, it carries with it the head 41 moving the connecting rod 40 to turn the actuating disc 37 on its journal 32. The initial movement allows the pin 38 to move in the slot 36, and thereafter to move the cam disc 33, such movement being slightly resisted by the spring pressed roller 42, but after the cam projection 34 has passed the roller 42, the action of the spring 44 accelerates the movement of the cam disc so as to turn the valve 14 with a snap action to bring the exhaust port 25 into registry with the inner end portion of the passageway 16.

During the first part of this movement the pin 38 is moved in the slot 36 into the position shown in Fig. 2, where it begins to turn the cam disc 33, but the valve 14 does not move because the pin 31 is in the slot 35 which allows the disc to turn without turning the valve. By the time that the cam projection 34 has moved beyond the spring pressed roller 42, the valve 14 is also being turned and which therefore allows the snap action of the spring pressed roller to move the valve, the slot 39 in the plate 28 limiting such movement. As the piston 20 is returned to its initial position shown in Fig. 9, by the expansive action of the spring 21, these actions are reversed to turn the parts so that by the time the piston is in its backward position, the valve 14 is also moved to the position shown in Fig. 9 and fluid is again admitted to the cylinder 19. The admission and cut-off of fluid is thereby controlled automatically by the action of the pistons.

The reciprocation of the pumping piston 8 in its cylinder forces the lubricant from the chamber 6 out through the cylinder 7 to the desired point where it is intended to be used.

I claim:

1. In a machine of the character described, a lubricant pump comprising a block having a chamber therein, a bushing extending through the chamber and having a plurality of relatively narrow peripheral slots therein elongated lengthwise of the bushing and located within the chamber, and a piston operatively mounted in the bushing.

2. In a machine of the character described, a lubricant pump comprising a block having a chamber therein, a bushing extending through the chamber and having a plurality of relatively narrow peripheral slots therein elongated lengthwise of the bushing and located within the chamber, a piston operatively mounted in the bushing for forcing lubricant therefrom, and an ex-

pansible packing washer attached to the end of the piston and having sides bearing against the sides of the bushing.

3. Lubricating apparatus comprising a structure having an enlarged chamber therein, a bushing extending through the chamber with the periphery thereof spaced from opposite side walls of the chamber providing open communication around the bushing within the chamber, said bushing having a plurality of relatively narrow radial slots therein elongated lengthwise of the chamber and located within the chamber providing communication therethrough from different sides of the chamber, and a pump piston operatively mounted in the bushing and having a cup washer at the free end thereof.

4. Lubricating apparatus comprising a block having an enlarged chamber therein open at the top of the block and approximately of uniform diameter from the top to the lower end thereof, a bushing extending through the chamber with the periphery thereof spaced from opposite side walls of the chamber providing open communication around the bushing within the chamber, said bushing having a plurality of relatively narrow radial slots in different sides of the bushing.

within the chamber, and a pump piston operatively mounted in the bushing and having a cup washer at the free end thereof.

5. In lubricating apparatus, a lubricant pump comprising a pump cylinder having a plurality of long narrow peripheral slots for admitting lubricant into the cylinder, and a piston operatively mounted in the cylinder and having an expansible packing member attached thereto.

6. In lubricating apparatus, a lubricant pump comprising a bushing forming a pump cylinder and having a plurality of long narrow peripheral slots therein being elongated lengthwise of said bushing, and a piston operatively mounted in the cylinder and having an expansible flexible packing member attached thereto.

7. In lubricating apparatus, a lubricant pump comprising a pump cylinder having a plurality of long narrow peripheral slots for admitting lubricant into the cylinder, and a piston operatively mounted in the cylinder and having expansible packing means attached thereto, the slots being of a width to prevent expansion of the packing means thereinto during operation of the piston.

ALBERT W. ARNOLD.
